ROTARY MIXER

Douglas W. Dron, Poughkeepsie, N. Y., assignor
to The De Laval Separator Company, New York,
N. Y., a corporation of New Jersey

Application May 24, 1951, Serial No. 227,988

1 Claim. (Cl. 259—68)

1

This invention relates to devices for effecting intimate mixtures of different liquids, and has for its principal object the provision of an improved mixer of the continuously-fed rotary type in which the extent or duration of the mixing action may be easily varied by increasing or decreasing the number of mixing stages.

In continuous processes for treating liquids, where an intimate mixing of different liquids is necessary, it is frequently desirable to change the extent of the mixing action. For example, in the refining of vegetable and animal oils, where the crude oil and an alkaline refining agent are passed continuously through a rotary mixer, some types of oil require a more prolonged mixing with the reagent than other types, if the proper mixing period is to be provided in each case. Some oils react better to slow speed intimate mixing and some to fast speed intimate mixing.

The mixer of the present invention is so constructed that it can be readily increased or decreased in size by varying the number of mixing stages and thereby adjusting the duration of the mixing time on the liquids passing through the device. A mixing device made according to the invention comprises a main housing section having an inlet passage or passages for the liquids to be mixed, and a drive shaft rotatably mounted in this section. A second or intermediate housing section is removably secured to the first section and forms therewith a closed mixing chamber for receiving the liquids from the inlet passage, the sections having interfitting faces to form a tight joint between the sections. Within the chamber is a rotary mixing member, preferably a disc having radial ribs or caulkings, which is secured to and driven by the drive shaft. An extension of this shaft is releasably connected to it and rotatable in a central bore in the second housing section. The latter section also has a flow channel leading from the mixing chamber to a second mixing chamber formed by the second section and a third section removably secured thereto, the third section having an outlet passage for the mixed liquids. This second chamber contains another rotary mixing member secured to and driven by the shaft extension, which is preferably held by part of the third section against endwise displacement and detachment from the main shaft. The second and third sections have interfitting faces identical with the interfitting faces of the first and second sections, respectively, so that the third section is adapted to fit against the face

of the first section to form a chamber similar to the first mixing chamber but having the outlet passage.

With this construction, the duration of the mixing action may be decreased by simply removing the second section, its shaft extension and the second mixing rotor from the assembly and securing the third or outlet section directly to the first or inlet section. Alternatively, the mixing action may be prolonged by inserting between the inlet and outlet sections, an additional section or sections similar to the second section, together with the shaft extension and mixing rotor for each additional section. Consequently, by providing several intermediate housing sections and corresponding shaft extensions with rotors, the number of mixing stages and therefore the mixing action and duration may be easily varied over a wide range.

20 In the preferred construction, each mixing rotor comprises a disc having a set of short radial ribs or caulkings staggered on each face. I have found that in this way a more vigorous agitation and a more intimate mixing of the liquids are obtained.

For a better understanding of the invention, reference may be had to the accompanying drawings, in which

Fig. 1 is a longitudinal sectional view of a preferred form of the new mixer;

30 Fig. 2 is a sectional view on the line 2—2 in Fig. 1;

Fig. 3 is an enlarged face view of part of one of the rotary mixing members; and

35 Fig. 4 is a view similar to Fig. 1 but showing the device with the intermediate housing section eliminated to provide only one mixing stage.

Referring to Figs. 1, 2 and 3, the device there shown comprises a main housing section 10 having at one end a flange 10a by which this section is connected to an electric motor 11, as by means of bolts 12. The motor 11 has a drive shaft 11a extending into a central bore in the housing section 10. The latter contains packing elements 13 surrounding the drive shaft and compressed against it by means of a sleeve 14, the sleeve being held against the packing by bolts 14a threaded into the central portion 10b of the main housing section.

40 At its opposite end, the main housing section 10 has a flange 10c secured to an intermediate housing section 16. The intermediate housing section 16 comprises a central hub 17 and flanges 18 and 19 extending radially from the ends of the hub. The flanges 10c and 18 have inter-

fitting faces 10d and 18a, respectively, and define a mixing chamber 20. A gasket 21 may be interposed between the faces 10d and 18a to prevent leakage from the mixing chamber. Within the chamber 20 is a rotary mixing member 22 in the form of a disc having a hub 22a. The disc hub is releasably secured to and driven by an extension 23 of the drive shaft 11a. As shown at 23a, the extension 23 is driven from shaft 11a through a releasable joint which enables the extension 23 to be withdrawn from the drive shaft. The main housing section 10 has separate inlet passages 24 and 25 which merge into an annular inlet passage 26 leading to the inner portion of chamber 20 around the hub 22a.

The hub 17 of the intermediate housing section has a central bore 17a for receiving the outer end portion of the shaft extension 23. It also has a series of arcuate channels 17b spaced around the bore 17a and leading from the mixing chamber 20.

A third housing section 28 is releasably secured to the flange 19 of the intermediate section 16 and forms therewith a second mixing chamber 29. The flange 19 and the housing section 28 have interfitting peripheral faces 19a and 28a, respectively, which are identical with the interfitting faces 10d and 18a, respectively.

A gasket 30 may be interposed between the faces 19a and 28a to form a tight joint. The section 28 has an axial boss 28b forming an outlet passage 31 aligned with the drive shaft 11a. A second rotary mixing member 32 is disposed in the chamber 29 and has a hub 32a secured to and driven by a shaft extension 33. The extension 33 extends into the central bore 17a of the intermediate section 16 and is driven from the extension 23 through a releasable joint 33a which permits the extension 33 to be withdrawn from the extension 23. At its outer end, the extension 33 has a reduced conical portion 33b rotatable in a socket formed by a spider 34 of housing section 28. Thus, the spider 34 supports the outer end portion of extension 33 for rotation in the housing and prevents separation of the shaft extensions 23 and 33 from each other or from the main shaft 11a.

The housing sections are secured together by releasable means comprising bolts 35 and 35a, to hold the faces 10d-18a and 19a-28a in interfitting relation. The bolts 35 extend through the peripheral portions of the housing sections and their respective interfitting faces.

The mixing rotors 22 and 32 are in the form of discs and are provided on both faces with radial ribs or caulk. As shown particularly in Fig. 3, each face of the disc 22 has a set of radial ribs or caulk 22b staggered around it. The mixing rotor 32 is identical to the rotor 22.

In the operation of the mixing device, the liquids to be mixed are delivered through the inlet passages 24 and 25 and the annular passage 26 into the central portion of chamber 20 around the rotor hub 22a. Due to the high speed rotation of the rotor 22 and the action of the staggered ribs or caulk 22b and 22c, the liquids are subjected to violent agitation in the chamber 20 to form an intimate mixture of the liquids. The mixture is forced to flow in a confined expanding path from the annular passage 26 to the outer portion of chamber 20, thence around the periphery of rotor 22, and then in a contracting path to the channels 17b in the hub of the intermediate section. The flow of the mixture in this manner, while in

contact with the rotating disc 22 and its radial ribs or caulk, facilitates the thorough mixing of the liquids and causes the liquid body to undergo rotation at high speed. The stationary channels 17b act to still the rotation of the liquid body as it discharges from the chamber 20 and thereby increase the mixing action. From the channels 17b, the mixture passes into the second mixing chamber 29 where it undergoes a mixing action similar to that in the first chamber 20. The mixture is finally discharged from the device through the outlet passage 31 of the second mixing chamber. It will be understood that the outlet section 28 of the housing may be provided with a suitable adapter (not shown) to facilitate connection of the discharge passage 31 to a pipe line for conveying the mixture to the next operation in the process. Similarly, the inlet section 10 of the housing may be provided with suitable adapters (not shown) to facilitate connection of the inlet passages 24 and 25 to the supply pipes for the liquids to be mixed.

For some purposes, the two stages of mixing as illustrated in Fig. 1 may be unnecessary or even undesirable. In such a case, the device may be readily converted to provide only a single stage of mixing, as illustrated in Fig. 4. As there shown, the intermediate housing section 16 has been removed by unfastening the bolts and nuts 35-35a, and the outlet section 28 has been secured directly to the inlet section 10. Thus, a single mixing chamber 36 is provided which is similar to the first stage chamber 20 (Fig. 1) except that it is provided with the outlet passage 31. Also, the second rotor 32 is omitted, and the shaft extension 33 is substituted for the extension 23 so that conical portion 33b is received in the socket of the spider 34. Consequently, the extension 33 is prevented from moving away from the main shaft 11a and breaking the releasable driving connection 33a between these parts.

If it is desired to add another stage of mixing to the two stages illustrated in Fig. 1, this may be accomplished by simply removing the outlet section 28, securing another intermediate section 16 to the flange 19, adding another rotor 22 and its shaft extension 23 in the intermediate chamber thus formed, and then reconnecting the shaft extension 33, rotor 32 and outlet section 28. It will be apparent that any number of mixing stages may be added in this manner, the section 28 and shaft extension 33 being located at the outer end of the final assembly, and the rotor 32 always being at the end operating against end bell 28.

I claim:

60 A device for mixing together different liquids, which comprises a housing section having an inlet passage for the liquids, a drive shaft rotatably mounted in said section, a second housing section removably secured to the first section and forming therewith a mixing chamber communicating with the inlet passage, said sections having interfitting faces to form a tight joint between the sections, the second section having a bore and a flow channel leading from said chamber, a shaft extension rotatable in the bore and detachably connected to said shaft, a third housing section removably secured to the second section and forming therewith a second mixing chamber communicating through the flow channel with the first chamber, said third section

having an outlet passage for mixed liquids, said second and third sections having interfitting faces identical with said first interfitting faces of the first and second sections, respectively, whereby the third section is adapted to fit against said face of the first section to form a chamber similar to the first chamber but having said outlet passage, releasable means for securing the housing faces in said interfitting relation, and rotary mixing members in the chambers secured, respectively, to said shaft and extension, said second section having a central hub containing said bore and channel and also having a flange extending radially from the hub at each end thereof, one of said faces being formed at the outer portion of each flange, said third section having an element engaging the adjacent end

of the shaft extension to support the same for rotation and surrounded by said outlet passage.
